UNITED STATES PATENT OFFICE.

FREDERICK MARQUART, OF CLEVELAND, OHIO.

VAPOR-STOVE.

SPECIFICATION forming part of Letters Patent No. 327,568, dated October 6, 1885.

Application filed August 30, 1884. Serial No. 141,872. (No model.)

To all whom it may concern:

Be it known that I, FREDERICK MARQUART, of Cleveland, in the county of Cuyahoga and State of Ohio, have invented certain new and useful Improvements in Vapor-Stoves, of which the following is a specification.

This invention relates to vapor-stoves, the object being to improve the construction of this class of stoves and to supply one or more burners from one generator.

The invention consists in the features of construction and combinations of parts herein-after fully described, and pointed out in the claim.

15 In the accompanying drawings, Figure 1 is a side elevation of the top or table of a vapor-stove having my improved generator and burners attached. Fig. 2 is a top or plan view of the generator and burners. Fig. 3 is an enlarged vertical section of my new generator. Fig. 4 is a perspective view of the generator.

20 A is a hollow ring, connected by an upright pipe, p, to the supply-pipe P, and is provided with three branch tubes, a a a, each having jet-orifices controlled by needle-valves v v v.

25 Depending from the ring A is a commingling-chamber, B, having one or more central air-tubes, b, and is also provided with a side tube, b', presenting its open end toward and opposite to the middle needle-valve v, located in a depending arm of the middle branch a. The said chamber B is fitted in the ring A up against an internal shoulder, where said chamber is covered by a perforated disk or diaphragm, d, through which also the central tube or tubes project. Above the said perforated disk d is placed a short wide tube, C, resting on an internal shoulder. This comprises the combustion-chamber.

30 Beneath the commingling-chamber B is lo-

cated a heater-cup, e, supported by the central tube b. Cup e has a branch, e', extending underneath the middle valve a v, which is designed for catching fluid from the valve and to conduct it into the cup e when required for 45 starting the generator.

D D are pipes leading to other burners, E E, attached to their outer ends. The inner ends of said pipes D D are curved or bent so as to present their open ends opposite to the 50 orifices and valves in the side arms a a.

The burners E E are constructed in a similar manner to the middle burner, and consist of a commingling-chamber, e, over which is fitted a ring or band for holding a perforated 55 disk or diaphragm, f, and a tube combustion-chamber, e', and central air tube or tubes g. The pipes D D are supported by suitable hangers or brackets, h, in their position relative with the center burner and generator. 60 The object of bending the tubes D at their inner ends is to have all the stems of the needle-valves extend forward alike for convenience of handling and operating.

Having described my invention, I claim— 65
In a vapor-stove, the combination, with the supply-pipe, of the generator and burner consisting of a ring, a commingling-chamber arranged within said ring and provided with a central tube or tubes, a perforated diaphragm 70 surrounding said tube and forming the top of said commingling-chamber, a tube leading from the jet-orifice to said commingling-chamber, and a tube leading from the generator to the jet-orifice, substantially as described.

FREDERICK MARQUART.
